STENCIL BLANK HOLDER

Robert E. Winebrenner, Hanover, Pa.

Application March 22, 1939, Serial No. 263,523

5 Claims. (Cl. 101—114)

This invention refers to stencils and more particularly to a device for holding same during use in marking. It has among its objects to provide a holder for stencil blanks that will retain the stencil blank in position for stencilling in a secure and substantial manner, to have the arrangement such that the hands of the user will be protected from the ink or paint used in making the markings; that will enable the stencil to be held more conveniently than with the fingers alone, and usable over a broader area about the user. Another object is to have the stencil constructed so that it may be used in various positions predetermined upon. A further object is to have the stencil that it may be controlled by the hand rather than by the fingers; that the device may be kept clean easily; that will be non-splashing; and will act as a guide for the stencil, and allow speedier stencilling. Other objects will become apparent as the invention is more fully set forth.

The usual manner of stencilling requires the placing of the stencil blank on the box or plane to be marked, and held by the fingers of the operator. The stencil brush is then passed across the stencil, and the mark appears on the surface treated. If the brush is pushed too strongly on the stencil blank, it is apt to displace same and cause the marking to blur or be erratic, because it is difficult to hold the stencil still with the fingers alone. The fingers usually have to be moved several times, when a large stencil is used, to allow the brush to operate properly, and no matter how careful the user is, he is apt to get inked, and the stencil blank displaced.

This may be due to the brush striking his fingers or because of the handling of the stencil after it is, or has been inked. This device does not require the hands or fingers to touch the stencil blank at all. It picks up the stencil at a distance from the fingers, through an open jaw, which closes tightly on same and retains the stencil in any position selected. The holder consists of a jaw member and a handle. The handle of the device is grasped by the hand and lifts the stencil blank like a stove lid is lifted. The stencil blank is laid on the surface to be marked by the holder and held securely by pressing on the handle and holding the jaw member firmly down on it. The brush is then manipulated with the other hand in the conventional manner, across the face of the stencil blank. The stencil blank is then lifted with the device and placed away, the jaw member being opened to allow it to fall out when the stencil blank is to be dis-

carded. The holder may then be easily wiped off to clean it, if there is any stencilling ink on it. It has a shield arrangement arranged at an angle that prevents the ink from the stencil splashing, when it strikes same, which shield also serves to stiffen the device and reinforce the stencil blank so that it will be held out straight and rigidly. Work may be done considerably quicker by using the holder, and with less spoiling of the work and user, than is possible without its use, and takes better care of the stencil blank. The special knurling on the gripping portion of the jaws prevents the stencil blank from getting out of line.

In the drawing is shown an embodiment of this invention, in which:

Figure 1 is a perspective view of a stencil holding device embodying this invention.

Figure 2 is a side elevation of the device indicated in Figure 1, with a dotted outline showing the position of the parts when open.

Figure 3 is a sectional detail of the swivel joint used with the handle of the device.

Figure 4 indicates a detail of the special knurling on the gripping portion of the jaw members.

Similar reference characters refer to similar parts throughout the drawing.

In the drawing 1 represents the outline of a conventional stencil blank which has letters or figures 2 cut out to provide the usual script to be copied on the surface to be marked. It is of the usual rectangular form and of oiled paper or card. The stencil blank is placed on a flat lower jaw member 3 which is hinged at 5 on a transverse bar 15, to an upper jaw member 4 which is bevelled down to meet the front portion of the member 3, and contact same, a spring 6 on the bar 15 being arranged between the two members to provide a closing pressure on same, to keep the jaws closed normally. The rear portion 7 of the upper jaw member is horizontal or practically parallel to the normal plane of the bottom or lower jaw member 3, and extends back over the rear portion of this member 3, but short of its upwardly extending flange 8, so as not to interfere with its movement when the jaws are opened. A back ridge limits the amount of stencil blank in the holder. The rear portion 7 has a swivel joint 9 as indicated mounted on it, and is connected with a handle 10 that may move in any direction and be locked in position by bolt means 11. The purpose of the swivel is to allow the device to be held in any position, so as to enable the stencil blank to be placed in the most convenient position with respect to the

work for inking. A non-splash shield 12 is mounted on the front of the upper jaw member 4 as indicated and at an angle of about 60 degrees to the horizontal plane of the stencil and above the hand level, to cover the upper jaw member and also prevent the brush from splashing, at the end of its stroke, if it is drawn towards the hand holding the device. The shield is longer than the jaws and also acts like a palette if the brush is drawn in the reverse direction. This is especially valuable, when too much ink or paint is placed on the brush, before stencilling. This convenience enables the operator to make his stencilling uniform and avoid the troubles of smudging and spoiling the stencil work frequently incurred. The flange 8 serves to prevent any ink or paint flowing back from the stencil onto the rear of the device, where it will soil the hands of the operator or material beyond the stencil space. It is very simple to insert the stencil blanks or remove same, as the bending back of the shield 12 between the thumb of the hand holding the handle 10 and the first finger on the lower jaw. This causes the upper jaw 4 to open and press against the spring 6, as it tips on the hinges 5. The removal of the thumb from the shield allows the jaw member 4 to snap back on the lower jaw or on the stencil blank placed on same. The stencil blank is placed in the proper position, there being ample provision for holding it in the device, and it cannot be drawn out of the jaws without considerable effort and trouble, unless the jaws are opened in the manner already described. The special knurling 16 runs transversely across the gripping portion of the jaw members and offers sufficient contact with the blank as to prevent it slipping out of place, when once the jaws close and contact it, and at the same time, does not injure the blank. The jaws, at this location, are slightly rounded.

While but one form of the invention is indicated in the drawing, it is not desired to limit this application for patent to the particular form indicated, unless otherwise limited by the prior art, as it is appreciated that other construction could be used, employing the same principles and coming within the scope of the appended claims.

Having thus described the invention, what is claimed is:

50 1. A stencil holder of the class described com-

prising in combination a plurality of jaws for holding stencil blanks, means for actuating same, a handle for supporting the jaws, and a shield mounted on the jaws.

2. A stencil holder of the class described comprising in combination, a lower jaw member having an upwardly extending flange thereon for limiting the placement of stencil blanks thereon, an upper jaw member hinged to the said lower jaw member, resilient means for retaining the jaws together and an angularly disposed shield attached to the last mentioned jaw members at the portion adapted for binding the stencil blank in the lower jaw member.

3. A stencil holder of the class described comprising in combination, a lower jaw member having an upwardly extending flange thereon for limiting the placement of stencil blanks thereon, an upper jaw member hinged to the said lower jaw member, resilient means for retaining the jaws together and an angularly disposed shield attached to the last mentioned jaw member at the portion adapted for binding the stencil blank in the lower jaw member, a variably disposed handle attached to the upper jaw member and arranged to be protected by the shield in all positions.

4. In a stencil holder, the combination of a plurality of jaws adapted to hold stencil blanks out flat and away from the jaws, and means for limiting the movement of the stencil brush used on the stencil blanks, against the jaws and guiding same away from the said jaws, and means for holding the jaws away from the user and permitting the same to hold the stencil blanks in variable predetermined positions, and means connected with the jaws for preventing stencil ink used on the said blanks from getting beyond the rear portion of the jaws.

5. In a stencil holder, the combination of a plurality of jaws adapted to hold stencil blanks out flat and away from the jaws, and means for limiting the movement of the stencil brush used on the stencil blanks, against the jaws and guiding same away from the said jaws, and means on the jaw for restricting the movement of the stencil blanks gripped by the same, and whereby said blanks will be kept securely in position by them when the jaws are closed.
